GUIDED MISSILE

John V. Sigford, Los Angeles, Calif., assignor to Minneapolis-Honeywell Regulator Company, Minneapolis, Minn., a corporation of Delaware

Filed June 23, 1959, Ser. No. 56,511

Term of patent 14 years

(Cl. D71—1)

FIG. 1

FIG. 2

FIG. 3

FIG. 4

FIGURE 1 is a side elevational view of a guided missile embodying my new design;

FIGURE 2 is a side elevational view thereof taken from the right of FIGURE 1;

FIGURE 3 is an end elevation, taken from the bottom of FIGURE 1, and

FIGURE 4 is a perspective view, on an enlarged scale, taken from the left of FIGURE 3.

I claim:

The ornamental design for a guided missile, substantially as shown.
